Primary Examiner—Philip S. Hyder*Attorney, Agent, or Firm*—McDermott, Will & Emery[57] **CLAIM**

The ornamental design for a tool handle, as shown and described.

DESCRIPTION

FIG. 1 is a front perspective view of a tool handle showing my new design;

FIG. 2 is a top plan view of the tool handle of FIG. 1;

FIG. 3 is a bottom plan view of the tool handle of FIG. 1;
FIG. 4 is a right side elevation view of the tool handle of FIG. 1;

FIG. 5 is a left side elevation view of the tool handle of FIG. 1;

FIG. 6 is a front elevation view of the tool handle of FIG. 1;
FIG. 7 is a rear elevation view of the tool handle of FIG. 1;
FIG. 8 is a front perspective view of a modified embodiment of the tool handle;

FIG. 9 is a top plan view of the tool handle of FIG. 8;

FIG. 10 is a bottom plan view of the tool handle of FIG. 8;
FIG. 11 is a right side elevation view of the tool handle of FIG. 8;

FIG. 12 is a left side elevation view of the tool handle of FIG. 8;

FIG. 13 is a front elevation view of the tool handle of FIG. 8; and,

FIG. 14 is a rear elevation view of the tool handle of FIG. 8.

The broken line portions of the drawing disclosure are for illustrative purposes only and form no part of the claimed design.
